(57) **CLAIM**

The ornamental design for an armored vehicle, as shown and described.

DESCRIPTION

FIG. 1 is a perspective view showing an armored vehicle showing our new design.

FIG. 2 is a top plan view.

FIG. 3 is first side elevation view.

FIG. 4 is a second side elevation view.

FIG. 5 is a front elevation view; and,

FIG. 6 is a rear elevation view.

The broken line showing of various features is for illustrative purposes only and forms no part of the claimed design. The broken line boundary and the area there within the cylindrical element depicted in FIGS. 1-2 forms no part of the claimed design.
